UNITED STATES PATENT OFFICE.

CHARLES FRANKLIN SMITH, OF TACOMA, WASHINGTON.

CLOTHES-DRYING RACK.

Application filed April 25, 1927. Serial No. 186,442.

This invention relates to improvements in clothes drying racks and has as one of its objects to provide a rack which may be conveniently mounted upon the wall of a room 5 and upon which articles of clothing and other laundry may be hung to dry.

Another object of the invention is to provide a drying rack so constructed that the suspension means for the clothing or the like 10 to be dried may be adjusted to assume a lowered position at the time the articles of clothing or other laundered articles are being arranged upon the supporting arms of the device and then adjusted to an elevated position 15 to suspend the said articles a suitable distance above the floor of the room.

In the accompanying drawings:

Fig. 1 is a view in front elevation of the upper portion of the rack embodying the invention;

Fig. 2 is a horizontal sectional view taken substantially on the line 2—2 of Fig. 1 looking in the direction indicated by the arrows;

Fig. 3 is a vertical sectional view through 25 the entire structure taken substantially on the line 3—3 of Fig. 1 looking in the direction indicated by the arrows;

Fig. 4 is a horizontal sectional view in detail taken substantially on the line 4—4 of Fig. 3 looking in the direction indicated by the arrows.

The rack embodying the present invention comprises upper and lower bearing brackets indicated by the numerals 1 and 2 respectively which are preferably secured by screws or other suitable fastening means 3 to a board 4 which may be disposed against the surface of a wall and secured to the studding of the wall by nails or screws and arranged 35 in upright position as shown clearly in Figure 3 of the drawings. The brackets 1 and 2 are provided with outstanding arms indicated respectively by the numerals 5 and 6, and the arms 5 and 6 are formed upon their 40 under and upper sides respectively with studs indicated by the numerals 7 and 8 respectively. It will be observed by reference to the drawings that the brackets 1 and 2 are of identical construction and that the brackets 45 are secured to the board 4 in relatively reversed position, so that the lower bracket 2 is inverted with respect to the bracket 1 and so that the studs 7 and 8 oppose each other on a vertical line. The rack further includes 50 clothes supporting means embodying a head which is indicated in general by the numeral

9 and which will presently be more specifically described, this head being mounted upon a supporting standard 10 which may be either in the nature of a cylindrical rod of 60 hard wood or a suitable length of pipe. In any event, the standard is provided in its upper and lower ends with sockets 11 and 12 respectively which accommodate the studs 7 and 8, the standard being in this manner 65 firmly supported in an upright position and spaced with respect to the forward side of the board 4.

The head 9 above referred to may be made of hard wood and is formed of any desired 70 contour but preferably with a transversely rounded outer side 13 and a flat rear side 14, the head being provided with a channel 15 in its rear side of a diameter to more or less snugly accommodate the standard 10, the 75 head being slidably adjustably mounted upon the said standard in the manner clearly shown in Figures 3 and 4 of the drawings. Means is provided, as will presently be explained, for holding the head in an elevated position and 80 for suitably guiding the head in its adjustment vertically along the standard, and the head is formed in its said outer side 13 with a number of sockets 16 which are radial to the vertical center line of the rear face of 85 the head. Preferably the sockets 16 will be located in two or more rows or series located one above another in suitably spaced relation as best shown in Figures 1 and 3 of the drawings, and clothes supporting arms 17 are 90 fitted at their inner ends into the sockets 16 and extend radially from the said head. These arms are preferably each in the form of a rod of wood or metal, hard wood being 95 found preferable for the purpose inasmuch as it is capable of sustaining the articles of clothing or the like to be dried and does not corrode when subjected to moisture.

In order that the head 9 may be vertically 100 adjusted upon the standard 10 from the lowered position shown in dotted lines in Figure 3 to the full line position shown in said figure, a cable 18 is secured at one end to an eye 19 upon the forward side of the head 9 and is trained over a pulley 20 which is suspended 105 from a hook 21 formed at the outer end of the arm 5 of the bracket 1. The cable is led downwardly and is provided at its lower end with a ring 22 which may be engaged with a hook 23 formed at the outer end of the arm 110 6 of the bracket 2 as clearly shown in Figure 3, and when the cable is so adjusted the head

9 will be supported in the full elevated position shown in full lines in the said figure and in Figure 1. It will be understood at this point that a slight downward pull upon the cable will permit of disengagement of the ring 22 from the hook 23 so that the cable may be paid out and the head 9 permitted to lower upon the standard 10 by gravity so as to assume the dotted line position shown in Figure 3.

In order to avoid any binding of the head 9 upon the standard 10, anti-friction guiding means is provided in connection with the head 9 for co-operation with the standard and this means will now be described. The means embodies a plate 24 of segmental form which is secured in any suitable manner upon the upper end of the head 9 with its chordal edge in registration with the rear face of the said head, and this plate is formed with an opening 25 and at each side of the rear portion of the opening with a pair of upstanding ears 26 between which is mounted an anti-friction roller 27 preferably of hard wood although metal or any other material found suitable for the purpose may be employed if desired. As clearly shown in Figure 2 of the drawings these rollers have their axes disposed substantially at right angles to each other so that the peripheries of the rollers engage or contact the standard 10 at spaced points at the rear side of the standard. A similar plate 28 is fixed upon the lower end of the head 9 and the said plate 28 is formed with an opening 29 corresponding to the opening 25 in the plate 24. The lower end of the head 9 is formed with a recess 30 located at the forward side of the lower end of the channel 15 of the head and pairs of spaced ears 31 are provided upon the upper side of the plate 28 and have anti-friction rollers 32 journaled between them and corresponding to the rollers 27. It will be observed by reference to Figures 3 and 4 of the drawings that whereas as the anti-friction rollers 27 contact the standard 10 at spaced points at the rear side thereof, the anti-friction rollers 32 contact the standard at spaced points at the forward side thereof and this is of advantage in view of the fact that the weight imposed upon the arms 17 by the damp articles of clothing and the like draped thereon, tends to overbalance the head 9 in a forward direction and as a consequence the rollers 27 and 32 so engage the rear and front sides of the standard 10, respectively, as to avoid any binding of

the head upon the standard. It will be observed by reference to Figures 3 and 4 that the ears 31 and the rollers 32 mounted therebetween are housed within the recess 30 and consequently the rollers do not come in contact with the bracket arm 6 when the head 9 is in full lowered position.

It is to be understood, of course, that various changes may be made, within the scope of what is claimed, without departing from the spirit of the invention.

In mounting the device embodying the invention, the board 4 is disposed and secured against the wall of the room in which the device is to be located and with its upper end located either in contact with or very close to the ceiling, so that the bracket 5 will be similarly located and, when the head 9 is in elevated position, it will be evident that the clothes supported by the arms 17 will be located near the ceiling of the room where the temperature is highest.

Having thus described my invention, what I claim is:

In a clothes drying rack, upper and lower bracket members comprising attaching portions adapting them to be secured to a support, the said bracket members including outstanding arms, studs projecting from the under and upper sides of the arms of the upper and lower brackets respectively, a standard extending vertically between the said arms of the bracket members and having socketed ends engaging said studs, a head having a channel in its rear side, the head being slidably assembled with said standard with the wall of the channel fitting the standard, whereby the head may be vertically adjusted, plates secured to the upper and lower ends of the said head and provided with aligned openings through which the standard extends, the plates constituting means for maintaining the head in slideable engagement with the standard, anti-friction rollers mounted upon the plate at the upper end of the head and engaging the rear side of the standard, anti-friction rollers mounted upon the plate at the lower end of the head and engaging the forward side of the standard, clothes supporting arms extending radially from the head, and means connected with the head and adjustable to elevate and lower the same along the standard.

In testimony whereof I affix my signature.

CHARLES FRANKLIN SMITH.
